United States Patent Office

Des. 214,570
Patented July 1, 1969

214,570

CLIMBING ROPE

Irwin Cohn, 746 West St., Leominster, Mass. 01453

Filed Sept. 17, 1968, Ser. No. 13,568

Term of patent 3½ years

Int. Cl. D21—03

U.S. Cl. D34—5

FIG. 1 is a front elevational view of a climbing rope showing my new design;

FIG. 2 is a cross-sectional view taken on line 2—2 of FIG. 1; and

FIG. 3 is a cross-sectional view taken on line 3—3 of FIG. 1.

The broken lines in FIG. 1 indicate indeterminate length.

I claim:

The ornamental design for a climbing rope, substantially as shown and described.
